UNITED STATES PATENT OFFICE.

WILLIAM GEORGE ABBOTT, JR., OF WILTON, NEW HAMPSHIRE, ASSIGNOR TO ATLANTIC
TERRA COTTA COMPANY, OF NEW YORK, N. Y., A CORPORATION OF NEW YORK.

ROTARY CUTTING-TOOL.

1,286,194.

Specification of Letters Patent.

Patented Dec. 3, 1918.

Application filed June 28, 1917. Serial No. 177,494.

To all whom it may concern:

Be it known that I, WILLIAM G. ABBOTT, Jr., a citizen of the United States, and resident of Wilton, in the county of Hillsborough and State of New Hampshire, have invented new and useful Improvements in Rotary Cutting-Tools, of which the following is a specification.

This invention relates to a device for cutting away or routing out the faces of objects of various kinds and is particularly designed for so-called rabbeting or cutting out depressions in the faces of plaster models from which are made building blocks or bricks of terra-cotta, cement, clay or similar materials, or for rabbeting the blocks themselves, this invention being a divisional continuation of my prior application Sr. No. 11,589, filed March 2, 1915, for cutting machines. It will be understood that the blocks are usually made in molds formed from plaster models, but the invention is equally applicable to recessing or rabbeting either the models or the blocks themselves, which are made in the molds, or for any other similar purpose.

In preparing blocks of this character it has been customary to dig out or chip out by hand depressions or recesses in the faces of the models corresponding to the desired contour of the faces of the blocks which are to be juxtaposed in building, and to plane off or level the surfaces surrounding the depressions so that a close and even joint may be secured between adjacent blocks, the depressions in the blocks usually being filled with cement or mortar. This method of forming the depressions, whether in the models or in the blocks themselves, is slow, crude and expensive, and it is a principal object of the present invention to provide a tool which will cut said depressions quickly, accurately and neatly without danger of breaking or cracking the work. Other objects of the invention are to provide a tool which is exceedingly simple and inexpensive to construct, which may be readily sharpened, which is adapted to be advanced either axially into the work or to be moved along the face of the work and which may be readily assembled and disassembled.

Other objects of the invention will be ap-

parent from the following description and the accompanying drawings, in which,

Figure 1 is a side elevation of one embodiment of the invention; 55

Fig. 2 is a front elevation of the embodiment shown in Fig. 1;

Fig. 3 is a top plan view of the embodiment shown in Figs. 1 and 2; 60

Fig. 4 is a side elevation of another embodiment of the invention;

Fig. 5 is a front elevation of the embodiment shown in Fig. 4; and

Fig. 6 is a top plan view of the embodiment shown in Figs. 4 and 5. 65

As fully described in my prior application, my improved cutting tool is a rotary tool intended first to be moved directly into the work along its axis, thereby to drill or rout a circular recess in the face of the work, and then to be moved along the face of the work in order to cut an elongate recess in the work. In order to cut either directly into the work or along the face of the work 70 it is necessary to provide cutting edges not only at the forward end of the tool but also along the lateral portions of the tool. To this end I provide a tool, the operative portion of which comprises a bail-shaped blade 80 1, which is preferably in the form of a band of metal and which is so shaped as to have cutting edges 2 and 3 at its forward end and cutting edges 4 and 5 at its sides. The lateral cutting edges are preferably disposed 85 obliquely with respect to the axis of the tool, and while I may make the entire lateral portions of the bail-shaped blade oblique to the axis of the tool, as disclosed in the parent application, I prefer to make only the 90 forward parts of the lateral portions oblique to the axis of the tool, making the extreme ends of the blade substantially parallel with the axis of the tool.

Thus, in the embodiment shown in Figs. 95 1, 2 and 3, the blade 1 having the forward cutting edges 2 and 3 and the oblique cutting edges 4 and 5 is provided with portions 6 and 7 which are disposed in planes substantially parallel with the axis of the tool. The lateral portions 6 and 7 are disposed equidistant from the axis of the tool and they are preferably mounted in recesses 26 in the periphery of a body having an ex-

terior surface of revolution concentric with the axis of the tool. While the body may be either solid or hollow, I preferably make it solid in the form of a disk, and while the 5 surface may have any suitable contour of revolution, as for example a conical contour as disclosed in the parent application, I prefer to make the elements of the surface substantially straight and substantially parallel 10 with the axis of the tool, that is, I prefer to employ a cylindrical disk. Such a disk is shown at 8 in Figs. 1, 2 and 3, and for the purpose of mounting the disk in a machine for driving the tool, a tapered shank 9 is 15 provided at the rear of the disk, to be used in the well-known manner.

The cutting blade 1 shown in Figs. 1, 2 and 3 is preferably formed in the following manner: A flat band of suitable metal is 20 first twisted at its central portion, namely, at 10, through an angle of approximately 30°. The band is then bent rearwardly at points 11 and 12 disposed equal distances from the central point on opposite sides of 25 the central point through angles of approximately 45°. The band is then bent in the same direction at points 13 and 14 through angles of approximately 45° so that the lateral portions 6 and 7 will lie along opposite sides of the disk 8. The bends at 30 points 11, 12, 13, and 14 are preferably disposed perpendicularly to the central line of the band of metal, although they may if desired be slightly oblique to the central line 35 of the band.

When the band is thus formed it presents salient cutting edges 2 and 3 facing in opposite directions on opposite sides of the axis of the tool, and it also causes the 40 oblique cutting edges 4 and 5 and the lateral cutting edges 15 and 16 to project outwardly a greater distance from the axis of the tool than the portions of the blade disposed to the rear of these edges, thereby 45 affording sufficient clearance for the cutting edges throughout the entire length of the blade. These cutting edges are preferably sharpened, and I prefer to grind the blade on the inside so that the cutting edges slope 50 inwardly. Obviously, the cutting edges 2, 4 and 15 disposed on one side of the axis face in one direction (Fig. 2), while the cutting edges 3, 5 and 16 disposed on the other side of the axis face in the opposite 55 direction. These edges may be sharpened either before or after the blade has been bent into the form shown, but it is preferably ground before being bent.

In the embodiment of the invention shown 60 in Figs. 4, 5 and 6, the structure is substantially the same as that shown in Figs. 1, 2 and 3, except in that the blade 1', instead of being bent twice on each side of the axis is only bent once on each side, 65 namely, at points 17 and 18, these bends be-

ing through substantially 90°. Obviously, instead of bending the blade sharply through 90°, the bends may be made more gradually so as to provide rounding corners having contours resembling the double bend contour 70 shown in Figs. 1, 2 and 3, but having smooth curves. The blade 1' is likewise twisted in the axial region to provide salient cutting edges 19 and 20, and is preferably provided with lateral cutting edges 21 and 22. While 75 the blade may be secured to the supporting member by brazing or in any suitable manner, it is preferably secured by means of screws 23 and 24.

The operation of the apparatus is as follows: When the tool is first advanced into contact with the work the forward cutting edges 2 and 3 first come into operation and as the tool advances into the work, the lateral portions of the blade come into operation. While the blade is ordinarily not advanced into the work a sufficient distance to bring the forward face of the disk 8 into the plane of the face of the work, the blades are preferably sharpened throughout the 90 portions lying along the opposite sides of the support 8 so that the tool may, if desired, be advanced into the work until the rear face of the disk 8 comes into the plane of the face of the work, and then be moved in parallelism with the face of the work so as to cut an elongate slot as described in the parent application. Where it is desired merely to ream a circular opening the tool may obviously be advanced to any desired 100 depth, the lateral portions of the blade not being utilized in this mode of operation.

The term "longitudinally of the axis of the tool" has been employed in the claims not only to refer to the portions of the blade 105 disposed in planes parallel to the axis of the tool, but also to portions of the blade, such as portions 4 and 5 in Figs. 1, 2 and 3, which are disposed in part longitudinally and in part transversely of the axis of the tool. 110

I claim:

1. A rotary tool of the character described comprising a band disposed transversely of the axis of the tool, the band being twisted in the region of the axis so as to have salient operating edges facing in opposite directions on opposite sides of the axis. 115

2. A rotary tool of the character described comprising a band extending radially in opposite directions from the axial region of the tool, the band being twisted in said region so as to have salient operating edges facing in opposite directions on opposite sides of said region, and means for supporting the band at its opposite ends. 120

3. A rotary tool comprising a substantially flat bail-shaped band extending symmetrically on opposite sides of the axial region of the tool, the band being twisted in said region so as to have salient edges fac- 130

ing in opposite directions on each side of the region.

4. A rotary tool comprising a substantially flat bail-shaped band extending symmetrically on opposite sides of the axial region of the tool, the band being twisted in said region so as to have salient edges facing in opposite directions on each side of the region, and means for supporting the band

10 at its ends.

5. A rotary tool comprising a substantially flat bail-shaped band extending symmetrically on opposite sides of the axial region of the tool, the band being twisted in 15 said region so as to have salient edges facing in opposite directions on each side of the region, and a member having a surface of revolution concentric with the axis of the tool, the ends of said band extending along 20 said surface and being secured thereto.

6. A rotary tool comprising a disk concentric with the axis of the tool, and a bail-shaped blade extending forwardly from the disk substantially in an axial plane of the tool 25 and having its ends secured to the periphery of the disk, the blade having salient cutting edges facing in opposite directions on opposite sides of the axial region of the tool.

7. A rotary tool comprising a disk concentric with the axis of the tool, and a bail-shaped blade extending forwardly from the disk substantially in an axial plane of the tool and having its ends secured to the periphery of the disk, the blade having salient 30 cutting edges facing in opposite directions on opposite sides of the axial region of the tool and having the cutting edges extending along at least a part of the portions of the blade which are disposed longitudinally of 35 the axis of the tool.

8. A rotary cutting tool comprising a cutting band disposed substantially symmetrically with respect to the axis of the tool, the band being twisted in the axial region of 40 the tool so as to have salient cutting edges

facing in opposite directions on opposite sides of said region and being bent on opposite sides of said region so as to form a bail-shaped blade.

9. A rotary cutting tool comprising a cutting band disposed substantially symmetrically with respect to the axis of the tool, the band being twisted in the axial region of the tool so as to have salient cutting edges facing in opposite directions on opposite sides 55 of said region and being so bent on opposite sides of said region that the ends of the band are disposed longitudinally of the axis of the tool and that portions intermediate said ends and said regions are disposed relatively obliquely to the axis of the tool.

10. A rotary cutting tool comprising a cutting band disposed substantially symmetrically with respect to the axis of the tool, the band being twisted in the axial region of the 60 tool so as to have salient cutting edges facing in opposite directions on opposite sides of said region and being twice bent on each side of said region so that the ends of the band are disposed in planes substantially parallel 65 to the axis of the tool and so that the portions intermediate the bends on each side are oblique to the axis of the tool.

11. A rotary tool of the character described, comprising a substantially cylindrical support concentric with the axis of the tool, and a bail-shaped cutting band secured 70 at its opposite ends to opposite sides of the periphery of the band.

12. A rotary cutting tool comprising a bail-shaped band disposed substantially concentrically with respect to the axis of the tool and being twisted in the axial region of the tool so as to present salient edges, the edges being ground on the inside throughout 75 the central and lateral portions of the bail-shaped band.

Signed by me at Wilton, New Hampshire,
this 21st day of June 1917.
